UNITED STATES PATENT OFFICE.

FREDERICK F. BEHRENS, OF SPRINGFIELD, OHIO.

FRUIT-HAMPER.

1,217,137.

Specification of Letters Patent. Patented Feb. 27, 1917.

Application filed July 16, 1915. Serial No. 40,218.

To all whom it may concern:

Be it known that I, FREDERICK F. BEHRENS, a citizen of the United States, residing at Springfield, in the county of Clark and 5 State of Ohio, have invented certain new and useful Improvements in Fruit-Hampers, of which the following is a specification.

My present invention relates to means for 10 facilitating the gathering of fruits and nuts, its object being to provide a hamper, whereby the fruit, when shaken or picked from a tree, may be received and conveyed into baskets or other suitable receptacles, without 15 injury thereto.

A further object of my invention is to 20 provide a device of the character described that is readily assembled, and that when assembled, will present a strong and staple article, and that when disassembled, will fold into a small, compact form.

A still further object of my invention is 25 to provide a means whereby my improved hamper may be adapted to fit any ordinary tree, and securely attach itself thereto.

With these and other objects of general utility in view, I have illustrated my invention in the accompanying drawings, in which—

30 Figure 1 is a side elevation of my improved hamper assembled around a tree;

Fig. 2 is a top plan thereof;

Fig. 3 is an inverted or under plan, and—

35 Figs. 4 and 5 are enlarged details of the special form of spike employed in securing the hamper to the tree.

Similar reference characters refer respectively to similar parts throughout the several views.

40 My hamper comprises, primarily, a rectangular, knockdown, tubular metal frame 10 suitably supported at its four corners, by adjustable legs 11, and a canvas 12 stretched across and secured thereto by clips 13. The 45 canvas is preferably divided into four like hoppers 12^a, each respective hopper leading to its funnel or mouth 14. The center of the canvas is cut away to receive the trunk of the tree, and a slit is cut from one edge of 50 the canvas to and terminating in this cut

out portion. The edges of the slit are provided with means, such as snaps or buttons 15, for closing the same after the canvas has been assembled around a tree. In order to accommodate the varying diameters of trees, 55 I provide an auxiliary canvas 16, adapted to be laced to the tree trunk at a point above the intersection of the canvas 12, and to flare out and cover the cut out or central portion thereof (Fig. 2).

As a means for holding the canvas 12 in position for securing the frame 10 rigid to the tree, I provide a chain 17, circumferentially disposed about the trunk thereof (Fig. 3) its two ends being joined by means of a 60 turnbuckle 18. This chain is adapted to pass through apertures 19 in a series of blocks 20, having spurs 21 extending from their inner sides, and eyes 22 protruding diametrically opposite thereto. These blocks 70 20 are connected to the frame 10 by means of suitable links 23. Also, the funnels 14 of the hoppers, are connected by means of similar links 24 to the chain 17 and the frame 10.

75 It will be apparent from the foregoing, that in assembling the hamper, first the frame 10 is set up around the tree and the canvases 12 and 16 put in place; then the chain 17 with its blocks 20 and links or rods 80 24 are assembled thereto; the chain is then drawn up by means of the turnbuckle 18, forcing the spurs 21 into the tree and also drawing the rods 23 and 24 taut, thus making the entire structure one of extreme rigidity.

Having thus described my invention, what I claim is:—

A fruit hamper comprising a frame, a canvas stretched across and secured thereto, an 90 auxiliary canvas superimposed and spaced away from said first mentioned canvas and flared to cover the central portion of said first mentioned canvas, said first mentioned canvas providing a plurality of hoppers, 95 means for securing said frame to the trunk of a tree, said means comprising a chain circumferentially disposed about the trunk of said tree, means for connecting the ends of said chain, blocks laced upon said chain 100

having inwardly protruding spurs and extending eyelets, means connecting said eyelets with the frame, and means for spacing the mouths of said hoppers from the frame 5 consisting of links connecting said mouths with the frame and chain respectively.

In testimony that I claim the foregoing

as my own I have hereto affixed my signature in the presence of two subscribing witnesses.

FREDERICK F. BEHRENS.
